MANUFACTURE OF CONTAINERS MADE OF
PAPER AND SIMILAR MATERIALS

Otto Kasdorf, Montevideo, Uruguay

Application July 8, 1937, Serial No. 152,658
In Germany May 22, 1936

9 Claims. (Cl. 93—60)

It has already been proposed to make sleeve-like containers of paper and similar materials from a blank in which folding creases have been impressed, more particularly at that part which is to form the closure which is to be folded. Another method of making folding creases consists in this, that the container which has already been wrapped and stuck to form a sleeve is introduced with its wall between rotatable folding or embossing members and to allow it to pass through between these folding members in the peripheral direction. Finally it has been proposed to insert into the prepared container a folding block which only partially fills the interior of the container, more particularly its closure part. By laying the container wall against this folding block by means of pressure applying jaws which are brought laterally towards it, not only folds are to be preliminarily pressed but the parts of the wall to be folded are already to be given a partial preliminary bend, for facilitating the closing of the container, which is effected after the container has been filled. The insertion of the forming block into the container body, the employment of a separate folding block for the closure part and the bringing up of a number of pressure applying jaws acting as patrices, which has to be effected in various directions, against the folding block which acts as the matrix, make this method inconvenient, time consuming and expensive. In contradistinction thereto the invention has for its object to provide an embossing device consisting substantially of a patrix and a matrix, which is suitable for providing containers which have been prepared in a sleeve-like manner with the necessary folding creases or folding edges required for the closure part which is to be folded. This is effected by giving the patrix the form of a plunger, the contours of which correspond substantially to the interior of the unfolded container whilst the matrix is made in the form of a hollow body the inside of the wall of which corresponds to the periphery of the unfolded container.

The raised places and the depression on the patrix and matrix may consist of folding ridges and corresponding grooves of a known kind, which during the straight line motion relatively to one another of the patrix and matrix are approached towards one another in parallel displacement and are pushed one into the other in the longitudinal direction to a greater or less extent, during which they press the container wall between one another and provide it with longitudinal folding creases.

The raised places and depressions on the patrix and the matrix may also be formed by surfaces which form an angle with one another and by means of which the circular or elliptical cross section of the container is transformed into an annular cross section. In doing this it is possible to cause the arcuate container wall to merge into the closure part either gradually or with a bounding edge extending preferably in an arcuate fashion. The surfaces on the patrix and matrix which form an angle with one another, may also be jointly used with folding ridges and grooves, so that for instance the convex folds are formed by the edges, where the surfaces abut against each other, whilst the concave folds or folding grooves are produced by means of folding ridges provided on the matrix and corresponding grooves provided on the patrix. Actually sharp folds may be produced at the place where the closure part merges into the container body through the patrix and matrix being formed at the place of transition with somewhat different diameters. The steps thus formed on the patrix and matrix will then produce in the container wall a sharp bend, by means of which, when the container is being closed, the folded in surfaces will be bounded at the bottom and undesired and irregular sharp bends will be avoided.

The device according to the invention can be made suitable for containers which narrow conically towards the closure part for cylindrical containers and for containers which flare conically towards the closure part. In all these cases the hollow body forming the matrix need not be capable of being taken apart as the embossing operation is effected entirely by the axial insertion of the patrix. There is of course no reason why the matrix should not be made divisible, for instance for cleaning purposes.

In the accompanying drawings constructional examples of the invention are illustrated.

Figure 1 shows a device for conically narrowing containers in an axial section.

Figure 2 is as to one half a plan view of the empty matrix according to Figure 1, and as to the other half a section through the patrix and the matrix on line II—II of Figure 1.

Figure 3 shows a container stamped by means of the device according to Figures 1 and 2 with the folds formed according to the folding grooves for preparing it for closing.

Figure 4 shows a device for cylindrical containers in axial section.

Figure 5 is a section on V—V of Figure 4. 55

Figure 6 shows a container stamped by means of the device according to Figures 4 and 5.

Figure 7 shows a device for conically flaring containers in axial section.

5 Figure 8 is a section on VIII—VIII of Figure 7.

In Figure 9 the folding lines and folding grooves of Figure 7 are replaced by surfaces at an angle with one another.

Figure 10 is a section on X—X of Figure 9.

10 Figure 11 shows in axial section a matrix similar to that of Figure 9 for the production of convex folding edges by means of surfaces at an angle to one another and of concave folding grooves by means of folding lines.

15 Figure 12 is a plan view of Figure 11.

Figure 13 shows the matrix of Figure 11 with the patrinx inserted in it and the container between them in the stamping position, the patrinx being shown in elevation and the matrix and the 20 container in axial section.

25 Figures 14 and 15 are perspective views of a container provided with folding edges and folding grooves by means of the device according to Figures 11 to 13, before being folded and after the 25 folds have been made corresponding to the folding edges and grooves.

The device according to Figures 1 and 2 consists substantially of the patrinx 1 and the matrix 2.

30 The patrinx is in the form of a truncated cone and may also be used as the mandrel for wrapping the container 3 which narrows conically towards the closure part. The patrinx 1 is provided with four folding ridges two of which are indicated at 6' and 7' in the right hand part of Fig.

35 2 and the matrix with four corresponding grooves 4'' to 7''. The patrinx also has two grooves 8' and 9' and the matrix two corresponding folding ridges 8'' and 9''. On the patrinx 1 with the sleeve 3 placed thereon being inserted into the matrix

40 2 or, conversely, the matrix 2 being pushed over the patrinx 1, the folding ridges will be displaced parallel to the associated folding grooves and approached to the latter, until, pressing the container wall between them, they engage a short

45 way one in the other. By this means the container sleeve is provided with slightly convex folding grooves 4 to 7 and the concave folding grooves 8, 9, which however suffice for folding the closure part together by hand or with the aid of

50 suitable closing tools. The lower bounding edges 10 to 12 of the folding part thus form themselves. Special means may however be provided for forming lower sharp bounding bends for the folding part, which means shall be herein- 55 after described.

The arrangement shown in Figures 4 and 5 corresponds substantially to that of Figures 1 and 2, but serves for stamping cylindrical containers. The patrinx 13 is a substantially cylindrical body

60 which is offset at 14 so that the lower part has a somewhat smaller diameter. On the offset part it is provided with longer folding ridges 15 and shorter folding ridges 16, which project to such an extent as to be flush with the peripheral part

65 of the cylinder 13, which is not offset. In a corresponding manner the matrix 17 has its lower part offset at the edge 18 so as to project inwardly, this inwardly projecting surface being provided with grooves 19, into which the folding ridges 15 and 16 can be inserted in the longitudinal

70 direction. In order to enable the container with the patrinx to be easily withdrawn again out of the matrix, it is preferable for the folding ridges to be formed only on the patrinx and for 75 the matrix to be provided only with grooves. In

this way only convex folding grooves are formed in the container 20, whilst it must have both convex folds 21 and also concave folds 22. This does not matter however, as the convex folding grooves suffice for enabling both the convex folds 5 and the concave folds 22 to be formed. The container 20 and, correspondingly, the patrinx 13 and the matrix 17, are arranged for the production of concertina like folds of the kind known per se. The lower sharp bounding bends 23, 24, 25 of the 10 folded in surfaces either form themselves or special means may be provided for this purpose which shall be hereinafter described. The arrangement according to Figures 7 and 8 corresponds substantially to that of Figures 1 and 2. 15 As however it is intended for containers which flare towards the closure part, the folding ridges, for instance 22, and the grooves, for instance 23, are formed not at the lower, but at the upper end 20 of the patrinx 24 and of the matrix 25.

In the arrangement according to Figures 9 and 10 the folding ridges and grooves are replaced by surfaces of the patrinx and of the matrix 27, which are arranged at an angle to one another and which abut against one another at the 25 longer edges 28 for the convex folds and at the shorter edges 29 for the concave folds and which merge gradually or at an edge 30 into the conical peripheral surface of the patrinx 26. As is shown in the left-hand half of Figure 10, the convex 30 curved peripheral surface of the patrinx at first merges into a flat surface 31 which gradually becomes concave, and then, as shown in the right-hand half of Figure 10, merges into two surfaces 32, 33 which join one another in the edge 29 and 35 are concavely inclined to one another.

In order to enable the patrinx 26 with the container 34 to be inserted into the matrix 27, the diameter d^1 of the patrinx 26 at the lower ends of the edges 29 must not be smaller than the diameter d^2 of the patrinx at the place at which the curved peripheral surface merges into the surfaces which are arranged at an angle to one another.

The patrinx 35 and the matrix 36 in Figures 11 45 to 13 are provided both with surfaces 37 arranged at an angle to one another for forming concave folding edges 38 and with folding edges 39 and associated folding grooves 40 for forming concave folding edges 31 of the container 42. The surfaces 37 at an angle to one another of the patrinx 35 and the corresponding surfaces 33 of the matrix are so formed that with their bounding edges 44' and 44'' they stand out slightly beyond the curved peripheral surface of the patrinx 35 or 50 form slightly depressed surfaces in the matrix 36. By this means the container 42 (Figures 14 and 15) is given at the lower bounding line slight sharp bends 44 for folding.

The features described in the various constructional examples may also be employed in combination with one another. The number of folding grooves or folding edges to be formed is of course optional, as it depends on the form of the container and on the number of corners, the style 65 and shape of the closure part. When making containers, the body part of which is of rectangular or polygonal cross-section, the folding grooves may be stamped throughout the whole length of the container. Sharp edges at the places of 70 transition in the patrinx and matrix should as far as possible be avoided, so that the paper will not be damaged.

What I claim is:—

1. A device for stamping folding grooves and 75

5 folding edges for the folding closure of containers made of paper and similar materials, comprising a patrinx and a matrix capable of axial motion with respect to one another for applying internal and external pressure to the container blank and provided with raised and depressed places capable of sliding one within the other during the stamping operation, said raised and depressed places extending for only a part of the length of the 10 patrinx and matrix.

10 2. A device as claimed in claim 1 and in which the raised and depressed places of the patrinx and the matrix have the form of ridges and associated grooves capable of displacement in the longitudinal direction parallel to one another.

15 3. A device as claimed in claim 1 and in which the raised and depressed places of the patrinx and the matrix have the form of surfaces at an angle to one another and capable of displacement parallel to one another.

20 4. A device as claimed in claim 1 and in which at the raised and depressed places of the patrinx and matrix, where the closure part merges into the body part of the container, the said parts 25 form an angle with one another along edges, which edges are capable of being brought towards one another during the relative motion of the patrinx and matrix.

25 5. A device as claimed in claim 1 and in which at the raised and depressed places of the patrinx and matrix, where the closure part merges into the body part of the container, the said parts 30 form an angle with one another along arcuate edges, which arcuate edges are capable of being

brought towards one another during the relative motion of the patrinx and matrix.

5 6. A device as claimed in claim 1 and in which at the raised and depressed places of the patrinx and matrix, which have the form of surfaces at an angle to one another and are capable of displacement parallel to one another, the said parts form where the closure part merges into the body part of the container, an angle with one another along edges, which edges are capable of being 10 brought towards one another during the relative motion of the patrinx and the matrix.

15 7. A device as claimed in claim 1 and in which at the raised and depressed places of the patrinx and matrix, which have the form of surfaces at an angle to one another and are capable of displacement parallel to one another, the said parts form where the closure part merges into the body part of the container, an angle with one another along arcuate edges, which arcuate edges are 20 capable of being brought towards one another during the relative motion of the patrinx and the matrix.

25 8. A device as claimed in claim 1 and in which the raised and depressed places of the patrinx and the matrix have the form of surfaces at an angle to one another and capable of displacement parallel to one another, the said surfaces merging gradually into one another.

30 9. A device as claimed in claim 1, characterized by the joint use of folding ridges and grooves for longitudinal folding edges and surfaces forming an angle with one another for transverse edges of the folding closure.

OTTO KASDORF. 35
